UNITED STATES PATENT OFFICE.

DENIS MACHELL HOLLINS, OF BLACKBURN, ENGLAND, ASSIGNOR TO DRAPER COMPANY, OF HOPEDALE, MASSACHUSETTS, A CORPORATION OF MAINE.

SELF-THREADING SHUTTLE FOR LOOMS FOR WEAVING.

1,091,432.

Specification of Letters Patent. Patented Mar. 24, 1914.

Application filed May 20, 1911. Serial No. 628,484.

To all whom it may concern:

Be it known that I, DENIS MACHELL HOLLINS, a subject of King George V of Great Britain, residing at Blackburn, in county of Lancaster, England, have invented certain new and useful Improvements in Self- Threading Shuttles for Looms for Weaving, of which the following is a specification.

This invention relates to self-threading shuttles for looms, and has for its object the provision of simple and efficient means for preventing or reducing to a minimum the wear on certain parts of the shuttle due to the friction of the yarn passing thereover. In self-threading shuttles for automatic looms, and it is to these that my invention particularly relates, there is provided a metal block or threading device suitably designed to automatically assume control of the thread as the shuttle is thrown across the loom, and first cause its introduction into a longitudinal thread passage and thence by means of a horn, as it is termed, through an entrance slot into a laterally extending or side delivery eye. It is usual to provide a shuttle of this type with steel pins, one at each side of the outer end of the delivery eye, for the purpose of resisting the wear of the thread on the wood of the shuttle and for the same purpose, at the inner end of the delivery eye, the threading device has been provided with a steel guide pin or prong around which the thread draws when its direction is changed to cause it to pass from the longitudinal thread passage to the delivery eye. When using such shuttles with certain classes of yarn, more especially woolen or worsted or other coarse yarns, it has been found that the eye pins and the guide pin or prong referred to wear very rapidly, so that in a short time they become so cut and scored as to render the shuttle useless. There have been other attempts to overcome the difficulty, one device for the purpose being shown and described in the specification of British Patent No. 11412 of 1906, according to which there was placed in a recess formed in the shuttle at the inner end of the delivery eye, a block of porcelain, glass, or other similar vitreous material having an upturned guide prong and upright abutments to present an eye and slot to register with the slotted delivery

eye and cause the wear of the thread to be transferred from the wood to such wear resisting block.

According to my present improvements, I dispense with the use of a steel guide prong and wear pins as in the prior patent referred to, and I also employ vitreous wear resisting surfaces, which however are formed and applied in a novel manner and are simpler and better adapted for coarse yarns than the previous construction.

In describing my invention, I shall refer to the accompanying drawings, in which—

Figure 1 is a plan view of part of a shuttle, the threading device of which embodies my improvements; Fig. 2 is a side elevation looking in the direction of the arrow A, Fig. 1, and Fig. 3 is a transverse section taken as on the line B—B, Fig. 2, looking in the direction of the arrow C, same figure.

Referring to the drawings, 1 represents the shuttle, 2 the bobbin recess therein, and 3 the threading device which may be of any well known suitable construction and in the instance shown comprises a metal block having a longitudinal thread passage 5 therein into which the thread first passes and from whence it is guided by a horn 6 through an entrance slot 7 into the laterally extending side delivery eye 8, in the usual and well known manner.

According to my present invention, I form along one side of the delivery eye 8, a lateral undercut recess 8' in which is secured by cement or the like, a block 9 of porcelain, glass, or similar material having a smooth, glazed, and very hard surface, vitreous in character, and possessed of sufficient toughness to withstand the blows to which the shuttle is subjected. The block may be further secured in position by means of a pin 10 driven vertically into the wood of the shuttle and engaging in a vertical notch or recess in the back of the block, as will be understood by an examination of Figs. 1 and 2. The block 9 forms one side of the delivery eye 8 and is suitably curved along its inner face as at 9' and at its outer end 9² to guide the yarn with a minimum of friction. The inner end 9³ of the block, which is also suitably curved or rounded off, projects beyond the inner end of the delivery eye 8 into the longitudinal thread passage 5 of the threading de-

vice, and terminates at or substantially at the longitudinal axis of the shuttle, the end 9³ of the block thus occupying the position usually occupied by the steel guide pin or 5 post in the ordinary constructions of shuttles of this type.

The wall of the longitudinal thread passage 5 is provided or formed with an inwardly extending inclined or curved shield 10 or cover 5' which extends immediately above and beyond the inwardly projecting end 9³ of the block 9, and guides the thread, as the latter is drawn into the thread passage on the shuttle being thrown across the loom, 15 into proper position around the said end 9³ of the block. As the thread is drawn off, therefore, it draws around the curved inner end 9³ of the block 9 into the delivery eye 8, along the hollowed out or curved face 9', 20 and passes out of the delivery eye 8 around the curved outer end 9² of the block. The opposite side of the delivery eye 8 is formed with an undercut recess 8² in which is secured, by cement or the like, a block 11 of 25 porcelain or similar vitreous wear resisting material having its inner face suitably curved or hollowed out and its ends suitably curved to guide the thread, when the shuttle is thrown in the opposite direction, from the 30 curved inner end 9³ of the block 9 to the outer end of the delivery eye 8.

The block 11 may, if desired, be further secured in position by a vertical pin in the same manner as has already been described 35 with reference to the block 9.

The shape of the blocks 9 and 11 and of the shield or cover 5' in the thread passage 5 may be varied according to the particular construction of shuttle and threading device or to suit requirements.

Having thus described my invention, what I claim and desire to secure by Letters Patent is:—

1. In a self-threading shuttle for looms, 45 the combination of a shuttle body and a threading device having a longitudinal thread passage, of a non-metallic guide block extending transversely of the shuttle body and having its inner end extending into the 50 longitudinal thread passage and beyond the wall thereof to form a non-metallic guide for the thread in its travel from the bobbin, and a shield or cover extending into the thread passage beyond the end of the non- 55 metallic guide block to guide the thread over the end of the guide block as the shuttle is threaded and to a position below the edge of the shield or cover that the thread may normally bear only on the non-metallic guide 60 block as it is drawn from the shuttle during weaving.

2. In a self-threading shuttle for looms, 65 the combination of a shuttle body and a threading device having a longitudinal thread passage, of a non-metallic guide

block extending transversely of the shuttle body and having its inner end extending into the longitudinal thread passage and beyond the wall thereof to form a non-metallic guide for the thread in its travel 70 from the bobbin, and a shield or cover extending into the thread passage beyond the end of the non-metallic guide block to guide the thread over the end of the guide block as the shuttle is threaded and to a position 75 below the edge of the shield or cover that the thread may normally bear only on the non-metallic guide block as it is drawn from the shuttle during weaving, the outer end portion of said non-metallic block having a 80 rounded surface forming one wall of the delivery eye, and a non-metallic block forming the opposite wall of the delivery eye.

3. In a self-threading shuttle for looms, the combination of a threading block having a longitudinally extending thread passage, and a vitreous thread guide disposed transversely of the threading block and having its inner end extending into the longitudinal thread passage and beyond the adjacent wall thereof, and a shield projecting downward from a point above the inner portion of the vitreous guide and having a lower edge portion extending into the longitudinal thread passage above the lower 90 portion of the thread guide and normally above and out of contact with the thread leading from the bobbin, said vitreous guide forming one side wall of the delivery eye and a separate vitreous block forming the 95 opposite side wall of said eye.

4. A shuttle having a delivery eye and a self-threading device providing a longitudinal thread-passage, a vitreous thread guide having its inner end projecting into the longitudinal thread passage to engage the thread as it is drawn from the bobbin and furnishing the guiding means for the thread as it moves from the longitudinal passage to the delivery eye, and a shield extending 105 transversely from one side of the longitudinal thread passage and having its lower edge portion in the thread passage opposite to and crossing the inner end of the vitreous thread guide above the normal position of 110 the thread.

5. A self-threading shuttle for looms, having a threading device provided with a longitudinal thread passage, and an undercut laterally extending recess, a vitreous block 112 having a rounded end projecting beyond the wall of the laterally extending recess into the longitudinal passage to afford a non-metallic guide for the thread in its travel from the bobbin, and having also an open face portion directed toward the end of the shuttle, and an outer rounded portion at the delivery eye, and a shield extending into the longitudinal thread passage to guide the thread to said vitreous block as the shuttle 118

is threaded, the edge of said guide being normally above and out of contact with the thread as it is drawn from the bobbin during weaving.

- 5 6. A shuttle having a self threading device providing a longitudinal thread passage, a vitreous thread guide extending transversely of the shuttle with its inner end beyond the adjacent wall of and extended
10 into the longitudinal passage and having an open bearing portion facing toward the end of the shuttle, a shield extending downward into the longitudinal thread passage

from above and extending beyond the inner end of the vitreous thread guide, the lower 15 edge of said shield crossing the inner end of said vitreous guide in the longitudinal thread passage above the thread after the shuttle has been threaded.

In testimony whereof I affix my signature in the presence of two witnesses.
